UNITED STATES PATENT OFFICE

141,975

DESIGN FOR A CONVEYER FRAME

Willard S. Campbell, Chicago, Ill.

Application April 25, 1945, Serial No. 119,181

Term of patent 14 years

(Cl. D55—1)

To all whom it may concern:

Be it known that I, Willard S. Campbell, a citizen of the United States of America, residing in city of Chicago, in the county of Cook, and State of Illinois, have invented a new, original, and ornamental Design for a Conveyer Frame, of which the following is a specification, reference being made to the accompanying drawing, forming a part thereof.

Referring now to the drawing, Fig. 1 is a side

elevational view of a conveyer frame embodying my new design; Fig. 2 is a top plan view and Fig. 3 is an end elevational view of the same; Fig. 4 is an enlarged detailed view as seen on line 4—4 of Fig. 3; and Fig. 5 is a side elevational view of my conveyer frame in inclined position.

I claim:

The ornamental design for a conveyer frame, substantially as shown.

WILLARD S. CAMPBELL.
